UNITED STATES PATENT OFFICE.

JOHN H. SHAW, OF NEW HAVEN, CONNECTICUT, ASSIGNOR TO SARGENT & COMPANY, OF NEW HAVEN, CONNECTICUT, A CORPORATION OF CONNECTICUT.

CASEMENT-WINDOW ADJUSTER.

1,426,415.

Specification of Letters Patent. Patented Aug. 22, 1922.

Application filed June 1, 1920. Serial No. 385,675.

To all whom it may concern:

Be it known that I, JOHN H. SHAW, a citizen of the United States, and residing in New Haven, county of New Haven, State 5 of Connecticut, have invented certain new and useful Improvements in Casement-Window Adjusters, of which the following is a full, clear, and exact description.

My invention relates to window adjusters 10 and, more particularly, to that type of devices by which a casement window may be held in any adjusted open position that is desired.

One object of my invention is to provide 15 an adjuster for casement windows which, when the window is opened to any desired position, will automatically hold the window in this position.

Another object of my invention is to produce 20 a device which will retain a casement window in any desired position and yet allow it to be moved from this position, when a positive force is applied to move it, without the tightening and loosening of 25 screws or other fastening devices.

To these and other ends the invention consists in the novel features and combinations of parts to be hereinafter described and claimed.

30 In the accompanying drawings:

Fig. 1 is a view in elevation of a casement window to which my invention has been applied;

Fig. 2 is a plan sectional view of the 35 same;

Fig. 3 is a view similar to Fig. 2 on a larger scale, but showing the window in closed position;

Fig. 4 is a view similar to Fig. 3 showing 40 the window in open position;

Fig. 5 is sectional view on line 5—5 of Fig. 3;

Fig. 6 is a detail sectional view of the 45 friction adjusting means;

Fig. 7 is a sectional view on line 7—7 of Fig. 6;

Fig. 8 is a detail view of the tapered plug which forms an important feature of my 50 invention.

While I have illustrated my invention as applied to a casement window, it will be understood that it is capable of use in other relations and is not to be limited to the exact form shown.

55 I have shown, at 10, in the drawings, a

casement window of usual form hinged to the frame 11 to swing outward about a vertical axis. The improved adjuster, referred to generally by the numeral 12, is pivoted to the window and frame on the vertical 60 pivot pins 13 and 14, respectively. The adjuster is thus mounted to swing about its pivots when the window is opened or closed.

My adjuster 12 consists of two telescoping tubes 15 and 16. In the embodiment 65 illustrated, I have shown the outer tube 15, flattened at the end, as at 17, which is provided with an aperture to receive the pivot pin 13 on the window 10, and the inner tube 16 flattened at its free end 18, and perforated to receive the pin 14. One of the pivot pins, 14, as shown in the drawings, is not provided with a head so that the tube 16 may be freely detached from the window casing.

Considering the operation of the parts thus far described, it will be apparent that as the window is moved from open to closed position, or vice versa, the adjuster 12 will be extended and contracted longitudinally, 70 the outer tube 15 sliding freely over the inner tube 16. This action must, of course, result from the fact that the pivot 14 is not coincident with the window hinge. It will be seen, then, that if some means is provided 75 to prevent or to render difficult, relative longitudinal movement of the parts 15 and 16, the window may be yieldably or adjustably held in the desired position. This is done in the following manner:

The enclosed end of the tube 16 is provided with longitudinal slits 19 and is internally threaded at 20. A tapered or conically shaped plug 21, threaded at 22, is provided and is of such a size that when the tube 16 is threaded on this plug for only a few turns, the tube and plug will slide freely in the cooperating tube 15. However, due to the taper of the plug, if the tube is threaded farther on the plug, the slotted 95 end of the tube will be caused to expand circumferentially and to frictionally engage the sides of tube 15 so that relative longitudinal movement of the two tubes will be rendered difficult. The amount of 100 friction and, consequently, the amount of force necessary to open the window or move one tube relatively to the other may be adjusted to any desired degree by turning the plug one way or the other in the tube 16.

In order to provide a convenient adjustment of the plug and to render the use of tools unnecessary for this purpose, the plug is provided with a polygonal or flattened 5 end 23 and the flattened end of the tube 15 is shaped at 24 to receive this flat end 23 and hold it against rotation. If, then, the tube 16 is forced into the tube 15 until the plug is in the position shown in Fig. 6, and 10 the free end of the tube 16 is grasped in the hand and turned, this tube may be turned and adjusted relative to the plug 21 which is held against rotation as shown and the friction between the two tubes adjusted 15 as desired.

In applying the adjuster to a window, the tube portion 15 is first secured on the window 10, as shown, and the pivot pin with its mounting is secured on the frame 20 11. The tube 16, with plug 21 threaded a short distance therein, is inserted in the tube 15 to such an extent that the plug 21 is in the position shown in Fig. 6. The tube 16 is then turned until the desired frictional 25 engagement between the two tubes is obtained and is then withdrawn far enough to allow the perforation in the end 18 to slip over the pin 14. The window may then be opened or closed to any desired position 30 by being grasped and sufficient force applied and when released will ordinarily be frictionally held in the adjusted position. If, due to wear, the tubes telescope too freely, a new adjustment may be made by merely 35 slipping the end 18 from off the pin 14 and after pushing the plug up to the position shown in Fig. 6, giving the tube 16 a fraction of a turn.

Due to the fact that the expansion of the 40 inner tube to a slight extent will cause the parts to bind, it only requires a fraction of a turn on the plug 21, to expand the inner tube from a size which will slide freely within the outer tube to a size which will bind tightly therein to hold the parts against accidental or unintentional movement.

It will be apparent that my invention is 50 capable of many modifications and of various uses, which lie within the spirit of the invention and within the scope of the appended claims.

It is evident that the member 16 might be provided with a threaded tapered end 55 and the plug 21, provided with an expandable hollow end to receive the tapered end of the member 16 and thereby be expanded to hold the parts 15 and 16 against movement. It will be seen, therefore, that my device is 60 very simple, consisting of an outer sleeve or tube member and two inner members, slideable in the tube member, and cooperating to expand one of these inner members to hold the parts against relative longitudinal movement.

What I claim is:

1. An extensible member comprising an outer tube member, an inner member, one end of which projects from said tube member, having its opposite end threaded, a plug 70 within said tube member and correspondingly threaded to engage said second member, and cooperating means on said tube and plug to hold the same against relative rotation. 75
2. In a device of the class described, a tube member, a threaded plug rotatably contained within said member and cooperating means on said plug and the interior of said tube to hold said plug against rotation 80 relative to said tube.
3. In a device of the class described, a tube member, a threaded plug rotatably contained within said member, one end of said tube and the adjacent end of said plug 85 being shaped to hold said plug against rotation in said tube.
4. In a device of the class described, a tube member and a plug slidably contained therein, said plug being rotatable in said tube member along some portions of the length thereof, and means at other portions of the length of said tube to hold said plug against rotation. 90
5. In a window adjuster, a tube member, 95 a second member freely slidable into said tube member, and means for yieldably holding said members against relative movement, said means becoming operative when said second member is rotated in said tube member.
6. An extensible element comprising two members longitudinally movable relatively to each other and having sliding frictional engagement with each other and means to 105 vary said friction upon the relative rotation of said members.
7. In an extensible member, an outer tube portion, an inner portion within said tube and frictionally held against sliding movement therein, and means for varying said friction by the relative rotation of said inner and outer portions. 110
8. In a device of the class described, two telescoping members, means within the outer member cooperating with the inner of said members to cause it to be frictionally held against telescoping movement, said means being held against rotation within said outer member. 115
9. In an extensible member, an outer tube portion, an inner portion frictionally held against sliding movement within the outer portion; and means for varying the frictional engagement between said portions, 120 said means including a plug cooperating with the inner portion and held against rotation within the outer portion. 125
10. An extensible member, comprising an outer tube portion, an inner member slideable 130

in said tube portion, a second member with-
in said tube portion, cooperating means on
said inner member and said second member
for expanding one of said members yield-
5 ingly to hold the same against longitudinal
movement in said tube portion, and means
to hold said second member against rota-
tive movement in said tube portion.

11. An extensible member, comprising an
10 outer tube portion, an inner member slidably
in said tube portion, a second member with-

in said tube portion, cooperating means on
said inner member and said second member
for expanding one of said members yield-
15 ingly to hold the same against longitudinal
movement in said tube portion, said means
becoming operative upon the relative rota-
tion of said tube portion and said inner
member.

In witness whereof, I have hereunto set 20
my hand on the 27th day of May, 1920.

JOHN H. SHAW.
